(57) **CLAIM**

The ornamental design for an interconnectable landscape edging module, as shown and described.

DESCRIPTION

FIG. 1 is a top perspective view of an interconnectable landscape edging module of the present invention;

FIG. 2 is a right side view of the interconnectable landscape edging module of FIG. 1;

FIG. 3 is a left side view of the interconnectable landscape edging module of FIG. 1;

FIG. 4 is a front elevational view of the interconnectable landscape edging module of FIG. 1;

FIG. 5 is a rear elevational view of the interconnectable landscape edging module of FIG. 1;

FIG. 6 is a top plan view of the interconnectable landscape edging module of FIG. 1;

FIG. 7 is a bottom plan view of the interconnectable landscape edging module of FIG. 1;

FIG. 8 is a top perspective view of an alternative embodiment of the interconnectable landscape edging module of FIG. 1;

FIG. 9 is a left side view of the interconnectable landscape edging module of FIG. 8;

FIG. 10 is a right side view of the interconnectable landscape edging module of FIG. 8;

FIG. 11 is a front elevational view of the interconnectable landscape edging module of FIG. 8;

FIG. 12 is a rear elevational view of the interconnectable landscape edging module of FIG. 8;

FIG. 13 is a top plan view of the interconnectable landscape edging module of FIG. 8; and,

FIG. 14 is a bottom plan view of the interconnectable landscape edging module of FIG. 8.
